DRY SHAVER

Gerson Silverstein, Brooklyn, N. Y.

Application July 2, 1948, Serial No. 36,621

6 Claims. (Cl. 30—43)

1

This invention relates to new and useful improvements in shaving razors, and, more particularly, the aim is to provide a novel and valuable razor characterized by the inclusion of a manual actuator to be intermittently oscillatably operated, a train of gears for being continuously driven by intermittent operation of said actuator, and a plurality of cutting blades to be simultaneously rotated by said gear train.

The new razor is of the so-called hoe type, having a handle and above the latter a head carrying the cutting means. The new razor also has a finely multitudinously perforated top shell shaped to conform to the path of travel of the cutting edges of the cutting means, and, therefore, in this respect, also, the new razor is analogous to the so-called electric razor.

A special feature of the present invention is that the cutting means is comprised of a plurality of thin flat blades, these adapted to be affixed to a common revolvable carrier; and the arrangement is such that, when said carrier as driven by the gear train is rotated, the blades are bodily moved through circularly orbital paths concentric with the axis of such rotation, thereby to have the cutting means incorporate a plurality of whirling blades.

Said blades may be arranged radially of said axis, or arranged at angles to such planes, but, as herein shown, they are in places radial to said axis; and while as many blades as desired may be used, they are herein shown, for example, as present to such a total as to have each blade, of a circumferentially arranged series of them over a predetermined length, or length subdivision, of the carrier, at 90° spacings one from another.

Another feature of the invention is that any of said blades is readily removable, for discarding the same and the substitution of a new blade, or for resharpening and replacement thereof on the carrier; and in this connection another object is to provide a carrier such that the blades may each be a standard blade such as is now commonly sold at trifling cost for few-shave use in such well-known hoe type razors as the Gillette, the Gem, the Ever-Ready, the Schick, and various others.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

2

Fig. 1 is an elevational view, partially broken away, showing the shaving razor constructed in accordance with the present invention.

Fig. 2 is a view similar to Fig. 1, but looking toward the right in the latter view.

Fig. 3 is a fragmentary view showing the upper part of the razor; this view, so far as the casing is concerned, being a vertical section taken on the line 3—3 of Fig. 2, and, so far as the cutting means is concerned, illustrating certain cutting blades as secured to a length subdivision of the carrier, with the other length subdivision of the carrier having omitted therefrom its complement of blades and the securing clips for the last-named blades.

Fig. 4 is a transverse vertical section, taken on the line 4—4 of Fig. 3.

Fig. 5 is a perspective view of one of said blade securing clips, detached; the clip here shown being arranged is that clip seen at the lower right in Fig. 4.

Fig. 6 is a perspective view of one of the like blades illustrated as forming part of the now being considered embodiment; this blade being a so-called Gem blade.

Fig. 7 is a fragmentary vertical section, taken substantially on the line 7—7 of Fig. 1; this view omitting certain parts appearing in Figs. 1 and 2.

Fig. 8 is a somewhat diagrammatic view, illustrating a modification.

The shaving razor, according to the modification of the invention shown in Figs. 1 to 8, includes a hollow casing formed of two opposed molded shell-like portions 15 and 16, and a cap section 17. The portions 15 and 16 may be molded of a suitable synthetic resin or plastic. The cap section 17 is preferably made of very thin sheet metal and provided with a plurality of small perforations 18, in the manner familiar in the electric shaver art.

The casing portions 15 and 16 are substantially duplicates, except that it is the portion 15 only which is provided interiorly with a pair of bosses 19 and 20 (Fig. 1) and except that it is the portion 16 only which is provided with a boss 41, see Fig. 2; although, as will be understood, one of the portions 15 and 16 is formed to the right hand and the other of these portions is formed to the left hand.

The purpose of the boss last-mentioned will be explained later; but, now referring to the bosses 19 and 20, the casing portion 15 is apertured in line with the center lines of these bosses, and such apertures are continued as bores through the said bosses, so that, before the cas-

ing portions 15 and 16 are coupled, screws 21 and 22 (Figs. 1 and 2) may be employed for engagement with internally threaded necks 23 and 24 (see also Figs. 3 and 7) integrally projected from a plate 25.

On said plate 25, as by way of a stub-shaft 26, a spur gear 27 is rotatively mounted; also, as by way of a stub-shaft 28, another gear 29 meshes with the gear 27; and also, as by way of a pivot pin 30, a suitable spring urged pawl 31 is rotatively mounted on one side of spur gear 27. This pawl is for permitting rotation of the gear 27 only in one direction, that indicated by the arrow 32 in Fig. 7; said pawl engaging the teeth of a multi-point star wheel 33 fixed to the gear 27, as at 34, for rotation therewith.

Half formed along an edge of the casing portion 15, and half formed along a matching edge of the casing portion 16, is a slot 35, for providing a field of oscillation for a manual actuator 36 for the gear 27; such actuator pivotally mounted as at 37 and rockably carrying a star-wheel segment 38 resiliently urged to meshing relation, rack and gear fashion, with the star wheel 33. At its lower end, the actuator 36 has a lip 36^a providing the upper wall of a recess formed in the actuator and wherein lies the end of the segment 38 where the latter is pivotally mounted on the actuator at 36^b; there being a wire spring 36^c for urging the teeth 36^a of said segment into meshing relation with the star wheel 33. Thus, on an inward stroke of the actuator 36, the segment 38 will drive the wheel 33 in the intended direction, while on an outward stroke of the actuator, said segment, unable to reverse the direction of rotation of said wheel because of the pawl 31, idly moves outward, with the wheel 33 meanwhile rotating as before under momentum.

The actuator 36 is, when unlatched, normally urged to its full line position shown in Fig. 2, by an expansile coil spring 39, one end of which engages an L-pin 40 fixed in the aforesaid boss 41, and the other end of which engages a straight pin rearwardly offset from the actuator 36.

In order to hold said actuator 36 retracted, as indicated in dot and dash lines at 36' in Fig. 2, the actuator is transversely slotted as at 43; this slot being so placed that when the actuator is thus retracted, said slot is, as indicated at 43', in line with the upper end of a catch 44 slidably mounted, as by a pin and slot connection indicated at 45, on a projection 46 partially integral with the casing portion 15 and partially integral with the casing portion 16. Said projection at opposite sides has upstanding ears 47 for holding the catch 44 to straight-line sliding movement, into and out of the slot 43.

The casing portions 15 and 16 are coupled by rivets or the like 48, 49 and 50, these respectively sent through matching apertures in the matching pairs of ears 51, 52 and 53, one ear of each pair being integral with the casing portion 15 and the other ear of each pair being integral with the casing portion 16.

Following securing in the casing portion 15 of the plate 25 and its carried parts, by the screws 21 and 22 as explained, and incidental to coupling of the casing sections 15 and 16 as just above described, the actuator 36 is pivotally mounted on the pin 37, and the cutting-means carrier (Figs. 3 and 4) is placed in operative position by mounting the opposite ends of a carrier-shaft 54 in suitable journaling means in said casing portions. On said shaft, at its cen-

ter, is fixed a spur gear 55, this gear for now meshing with the gear 29, as shown.

The cap section 17, all around its bottom, has a downwardly outwardly offset flange 18', for readily removable securement to the tops of the casing portions 15 and 16, as by a pair of screws 18".

Referring next particularly to said carrier and to the cutting means as these are shown in the embodiment illustrated, and in these connections referring especially to Figs. 3-6, at each opposite side of the gear 55 is one of a pair of like carrier sections 56 and 57, both these sections, like said gear, suitably fixed on the shaft 54. Each carrier section is shaped for having four cutting blades removably mounted thereon. To clarify the drawing disclosure, the carrier section 56 only is shown as having its blades, respectively marked 58, 59, 60 and 61, in place thereon. 10 Each of the two carrier sections 56 and 57, over each of the four quadrants of the cross-sectional aspect thereof, is identical; with, at each of said quadrantal cross-sectional areas, as indicated in Fig. 4, a projected formation of truncated triangular outline, in which view one of said formations is marked 62.

Each such formation has a wall 63 lying in a plane approximately including the axis of the shaft 54, said plane substantially radially extended relative to said axis. Each such formation at its side opposite to the wall 63 has a wall 64 which, lying in a plane at an angle to a plane radial to said axis, may well be called a secantial plane. Each such formation also has a drilled and tapped recess 65 in its wall 63, with the axis of said recess normal to the plane of said wall. Opposite said wall 63, between the latter and the shaft 54, is a slot 66, this for accommodating a familiar reinforcement marked 67 in Fig. 6 and 20 permanently affixed to the blade there shown. Said blade also is characterized by the inclusion of a substantially elongated slot 68. Matchingly placed relative to this slot, when said blade is properly positioned relative to the formation 62, 30 is a slot 69 through the outer end of said formation. The last-named slot, for that one of said formations which is downwardly directed in Fig. 4, is given the same reference numeral, 69, in Fig. 3.

Each of the blades, having been placed as just explained relative to the formation 62 or to one of the three other formations corresponding thereto, is secured in position on and locked to its carrier section 56 or 57 by an L-shaped 40 clip 70 individual to each blade, all these clips being alike. Each of them is apertured at 71, and carries a projection 72; said aperture and projection being so arranged on a clip that when a blade and its clip are arranged relative to the carrier as shown, with said projection of said clip passing through the slot 68 of said blade and also into the related slot 69 of the carrier, the aperture 71 of said clip registers with the related drilled and tapped recess 65 of the carrier. Then, 50 merely by applying and tightening one of the eight screws 73 with slenderized knurled heads, the blade is anchored to a carrier section.

In operation, the actuator 36 having been unlatched from the catch 44, and with the handle portion of the device manually grasped, the hand of the user is intermittently flexed and relaxed, thus intermittently to thrust in the actuator 36, and thereby, through the star wheel 33 and the gear train 27-29-55, the carried is rapidly rotated, whirling the cutting blades at

high speed, with the cutting edges of said blades travelling through the path indicated at 74 in Figs. 3 and 4. At the same time, the device is manipulated to apply the finely perforated cap section 17 to the face or other body part to be shaved, thereby to cause the too-long hair ends to enter into such perforations for being cut off scythe-fashion by the whirling blades.

Referring finally to Fig. 8, this illustrates a modification in which two cutting blade carriers are provided, one axially alongside the other. Here the parts to which are applied reference numerals with single primes or double primes added correspond, respectively, to the parts to which are applied reference numerals without primes. The parts, operatively beyond the gear 27', and to which reference numerals with single primes are added, are for driving the carrier for the blades 58', 59', 60' and 61'. The shaft for the carrier for the blades 58'', 59'', 60'' and 61'' is indicated at 80, and the gear, fixed on said shaft and corresponding to the gear 55', is marked 81. Interposed between the gears 27' and 81 is a pair of spur pinions 82 and 83. Thus, when the actuator 36'' is operated as above described in connection with the actuator 36, the gears of Fig. 9 simultaneously rotate in the directions of the small arrows there shown, thereby to whirl all the cutting blades on the two carriers. To clarify and simplify Fig. 9, there is omitted therefrom a showing of the casing and of a plate for functioning as does the plate 25 relative to all gears other than a gear coaxial with a carrier.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a hand-power-operated shaving razor having a hollow casing providing a handle and a perforated end portion shaped interiorly to carry a chamber for a cutting means, a cutting means within the chamber, said cutting means comprising a rotatable carrier and a plurality of individually removable cutting blades on the carrier with each blade extended toward its cutting edge outwardly of the axis of rotation of the carrier, said blades being arranged on the carrier in planes substantially radial to said axis, for locking a blade in its placement on the carrier, said locking means comprising a clip, means for detachably connecting said clip to the carrier, and a projection carried by the clip for interlocking with said blade and with the carrier.

2. In a hand-power-operated shaving razor having a hollow casing providing a handle and a perforated end portion shaped interiorly to carry a chamber for a cutting means, a cutting means within the chamber said cutting means comprising a rotatable carrier and a plurality of individually removable cutting blades on the carrier with each blade extended toward its cutting edge outwardly of the axis of rotation of the carrier, said blades being arranged on the carrier in planes substantially radial to said axis, means for locking a blade in its placement on the carrier, said locking means comprising a clip, means for detachably connecting said clip to the carrier, and a projection carried by the clip extended through an aperture in said blade and

into a complementary aperture in said carrier.

3. In a hand-power-operated shaving razor having a hollow casing providing a handle and a perforated end portion shaped interiorly to carry a chamber for a cutting means, a cutting means within the chamber, said cutting means comprising a rotatable carrier and a plurality of individually removable cutting blades on the carrier with each blade extended toward its cutting edge outwardly of the axis of rotation of the carrier, said blades being arranged on the carrier in planes substantially radial to said axis, means for locking a blade in its placement on the carrier, said locking means comprising a clip, means for detachably connecting said clip to the carrier, and an elongated projection carried by the clip for extending through an elongated aperture formed in the blade and into a complementary elongated aperture formed in said carrier.

4. In a hand-power-operated shaving razor comprising a hollow casing providing a handle and a perforated end portion shaped interiorly to carry a chamber for a cutting means, a cutting means comprising a rotatable carrier and a plurality of individually removable cutting blades on the carrier with each blade extended toward its cutting edge outwardly of the axis of rotation of the carrier, an oscillatable actuator carried by said handle, and a gear train in the casing and operatively connecting the actuator and the carrier whereby intermittent oscillation of the actuator continuously rotates the carrier thereby to whirl said blades bodily through a circular path orbital to said axis, said blades being arranged on the carrier in planes substantially radial to said axis, means for locking a blade in its placement on the carrier, said locking means comprising a clip, means for detachably connecting said clip to the carrier, a projection carried by the clip extended through an aperture in said blade and into a complementary aperture in said carrier, said connecting means including an aperture through said clip, a drilled and tapped recess in the carrier aligned with the aperture of said clip, and a screw having a threaded shank passed through the aperture last-named and threaded into said recess.

5. In a hand-power-operated shaving razor comprising a hollow casing providing a handle and a perforated end portion shaped interiorly to carry a chamber for a cutting means, a cutting means comprising a rotatable carrier and a plurality of individually removable cutting blades on the carrier with each blade extended toward its cutting edge outwardly of the axis of rotation of the carrier, an oscillatable actuator carried by said handle, and a gear train in the casing and operatively connecting the actuator and the carrier whereby intermittent oscillation of the actuator continuously rotates the carrier thereby to whirl said blades bodily through a circular path orbital to said axis, said blades being arranged on the carrier in planes substantially radial to said axis, means for locking a blade in its placement on the carrier, said locking means comprising a clip, means for detachably connecting said clip to the carrier, a projection carried by the clip extended through an aperture in said blade and into a complementary aperture in said carrier, said connecting means including an aperture through said clip, a drilled and tapped recess in the carrier aligned with the aperture of said clip, and a screw having a threaded shank passed through the aperture last-named and

threaded into said recess, said clip being a substantially L-shaped strip.

6. In a hand-power-operated shaving razor comprising a hollow casing providing a handle and a perforated end portion shaped interiorly to carry a chamber for a cutting means, a cutting means comprising a rotatable carrier and a plurality of individually removable cutting blades on the carrier with each blade extended toward its cutting edge outwardly of the axis of rotation of the carrier, an oscillatable actuator carried by said handle, and a gear train in the casing and operatively connecting the actuator and the carrier whereby intermittent oscillation of the actuator continuously rotates the carrier thereby to whirl said blades bodily through a circular path orbital to said axis, said blades being arranged on the carrier in planes substantially radial to said axis, means for locking a blade in its placement on the carrier, said locking means comprising a clip, means for detachably connecting said clip to the carrier, and a projection car-

ried by the clip for interlocking with said blade and with the carrier, said clip having a pair of angularly offset walls, one of said walls having an aperture and the other of said walls carrying 5 said projection.
